CLAIM

The ornamental design for a stranded string light, as shown and described.

DESCRIPTION

FIG. 1 is a top, front and right side perspective view of a stranded string light showing my new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 in FIG. 1.

The broken lines in the drawings illustrate portions of the stranded string light which form no part of the claimed design. The dash-dot-dash broken lines show the boundaries of the enlarged views and form no part of the claim thereof. The oblique shade lines in the drawings represent transparent surfaces.

The stranded string light is shown with a symbolic break in its length. The appearance of any portion of the article between the break lines forms no part of the claimed design.
